UNITED STATES PATENT OFFICE.

WILLIAM E. SHEPHERD, OF TERRE HAUTE, INDIANA.

IRONING-TABLE.

1,172,064.

Specification of Letters Patent. Patented Feb. 15, 1916.

Application filed December 13, 1915. Serial No. 66,574

To all whom it may concern:

Be it known that I, WILLIAM E. SHEPHERD, a citizen of the United States, residing at Terre Haute, in the county of Vigo and State of Indiana, have invented a new and useful Ironing-Table, of which the following is a specification.

The present invention appertains to ironing tables.

10 The object of the invention is the provision of a sleeve or supplemental board and novel means for supporting it from the main board, a table or bench top, or other suitable support.

15 The present structure having the foregoing improvements is nevertheless simple and inexpensive, as well as being practical, serviceable and efficient in use, and the structure reduces to a minimum the number 20 of metallic parts employed which are liable to rust or corrode.

With the foregoing and other objects in view which will appear as the description proceeds, the invention resides in the com-

25 bination and arrangement of parts and in the details of construction hereinafter described and claimed, it being understood that changes in the precise embodiment of the invention herein disclosed can be made 30 within the scope of what is claimed without departing from the spirit of the invention.

The invention is illustrated in the accompanying drawings, wherein:—

Figure 1 is a side elevation of the ironing 35 table, a portion thereof being broken away, and the sleeve or supplemental board being applied thereto. Fig. 2 is a bottom plan view of the structure. Fig. 3 is a vertical section of the device converted into a step 40 ladder. Fig. 4 is an enlarged vertical section illustrating the stand for the sleeve or supplemental board, and the adjacent portions of the main and supplemental boards.

45 Figs. 5, 6 and 7 are bottom views of different supplemental boards which can be used. Fig. 8 is a side elevation of a modified form of stand for the supplemental board. Fig. 9 is a plan view of the stand illustrated in Fig. 8.

50 The table embodies the main ironing board 1, and a pair of inclined legs 2 having their upper ends pivotally connected, as at 4, to a transverse cleat 3 secured to the lower surface of the board 1 adjacent the butt end 55 thereof. A transverse slat 5 is secured to the lower edges of the legs 2 adjacent the upper

ends thereof, and a second transverse slat 6 is secured to the upper edges of said legs adjacent the lower ends thereof. A second pair of reversely inclined legs 7 is disposed 60 between the legs 2, and said legs are pivotally connected between their ends by a transverse rung 8. The legs 7 are connected between the rung 8 and the lower ends of said legs by other transverse rungs 9, and forming with the rung 8 and legs 7 a ladder which enables the device to be used as a step ladder, as will hereinafter more fully appear. The upper ends of the legs 7 are cut obliquely, and have attached thereto an 70 oblique transverse bar 10 disposed in a vertical or approximately vertical plane. The bar 10 is engageable with a series of transverse cleats 11 secured to the lower surface of the board 1 adjacent the tip end thereof. 75 The height of the board 1 can be adjusted by engaging the bar 10 behind the various cleats 11 which are spaced apart for that purpose, and the table may thus be adjusted to suit the user.

80 The table is equipped with means for holding the sad iron, said means embodying a horizontal supporting plate 12 having one end pivoted, as at 13, to a plate 14 secured to the lower surface of the board 1 at one 85 corner thereof and adjacent the butt end of the board, whereby the plate 12 can be swung under the board out of the way or so as to project from the board for supporting the sad iron when it is not being used. The 90 plate 12 has marginal depending flanges 15 for reinforcing or strengthening it, said plate or holder being readily stamped from suitable sheet metal, and the plate is provided with a depression 16 for accommodating 95 the iron and preferably of such a shape as to hold the iron in place. The plate 12 can be lined with asbestos or other heat insulating material. This device forms convenient means for holding the iron, where 100 it can be readily reached.

105 For convenience in the use of the structure as a step ladder, a chain or other flexible element 17 is connected, as at 18, to the lower surface of the board between the ends thereof, and said chain is provided at its free end with a hook 19 normally engaged with an eye 20 secured to the lower surface of the board, to prevent said chain from hanging loosely from the board when the chain is not in use. Attached to the rung 8 is an eye or attaching element 21 with which

the hook 19 is engageable, when the structure is converted into a step ladder. To do this, the legs 7 are swung between and into alignment with the legs 2, so that the legs 7 rest against the slats 5 and 6, and the board 1 is then set on end, with its tip or smaller end upon the floor or supporting surface. The hook 19 of the chain 17 is then engaged with the eye 21, to hold the legs and board 1 at the proper angle, to prevent their separating, and the rungs 9 and 8 then enable a person to step or climb up the ladder for hanging curtains, pictures, and the like.

Various sleeve or supplemental boards 15 can be used with the main board 1, three of such supplemental boards being illustrated in Figs. 5, 6 and 7. The board 22 illustrated in Fig. 7 is especially useful for padding and shaping the shoulders of garments, 20 pressing said sleeves and shoulders as well, forming collars, cuffs and pressing same, ironing laces, ribbons, handkerchiefs, and the like. The board 22' illustrated in Fig. 6 is adapted especially for heavy work of 25 all kinds in the home or factory, for the bodies of garments, for steaming and pressing garments, especially trousers. The board 22'' depicted in Fig. 5 is useful for the making and ironing of infants' or children's garments having small sleeves, for ironing waists gathered at the shoulders, neck bands, garments cut with yokes, and garments with collars attached thereto. These and other forms of supplemental 30 boards may be used, but the use of the board 22 is especially referred to hereinafter although it is to be understood that the description will apply to other supplemental boards as well.

40 In order to support the board 22 above the board 1, a stand 23 is employed, embodying transverse vertical plates or boards 24 and 25, and a longitudinal board or web 26 is disposed in a vertical plane and having its 45 ends secured to the plates 24 and 25. The plate 24 and web 26 are adapted to rest upon the board 1, which may be taken to represent any suitable board or support, and the lower edge of the plate 24 is provided with a 50 depending tenon 27 to drop into a socket or bore 28 with which the board 1 is provided. Said board is preferably provided with a series of sockets 28, enabling the stand 23 to be adjusted to various positions between 55 the edges of the board, as may be found most convenient for the user. The rear plate 25 projects below the front plate 24, and is provided with a transverse groove 29 engageable with the butt end of the board 1, 60 to assist in holding the stand firmly in place. In applying the stand, the groove 29 is engaged with the end of the board 1, and the stand is then swung to drop the tenon 27 in the respective socket 28, which will hold the 65 stand rigidly in position.

The supplemental board 22 rests upon the stand 23, and is removably attached thereto. Thus, a plate 30 is secured to the rear or outer surface of the plate 25 adjacent its upper end, and is provided with an angularly extending lip or flange 31. A transverse cleat 32 is secured to the lower surface of the board 22 between the ends thereof, and is adapted to rest against the plate 24, and a transverse strap 33 is terminally secured to the lower surface of the board 22 adjacent the butt end thereof, and has a downwardly offset bridge portion 34 engageable with the lip 31 by a longitudinal movement of the board 22 relative to the stand 23. To apply the board 22 to the stand, the strap 33 is moved longitudinally into engagement with the lip 31, with the other end of the board raised slightly, and when the board 22 is moved to position, the same will swing downwardly onto the stand 23, the cleat 32 moving downwardly against the side of the plate 24, as seen in Fig. 4. This will hold the board 22 rigidly upon the stand 23, and said board can be readily detached from the stand. The boards 22' and 22'' are also provided with the cleat 32 and strap 33, but the board 22'' is provided with a second strap 33 in front of the cleat 32, whereby the board 22'' can be applied to the stand in reversed positions for the advantageous use of said board.

In Figs. 8 and 9, a modified form of stand 23' is illustrated, the same embodying the plates 24' and 25' adapted to rest upon the board or other support 1', and a web 26' attached to the plates. The board is secured upon the stand 23' the same as with the stand 23, a plate 30 being secured to the plate 25' for that purpose. The stand 23', however, is adapted to be used not only upon an ironing board, but upon the top of a table, bench, dresser, and various other articles of furniture. To this end, an L-shaped bracket has its vertical arm secured to the plate 25', and a clamping screw 29' is threaded through the lower arm of said bracket and has a padded end adapted to contact with the lower surface of the support 1', to clamp the stand upon the support. This stand 23' can be applied to various supports having a projecting edge.

Having thus described the invention, what is claimed as new is:

1. In a device of the character described, a stand, a board adapted to rest thereon, said board and stand having means to interengage with one another when the board is moved longitudinally relative to the stand, and a transverse cleat carried by the lower surface of said board and adapted to move downwardly into engagement with said stand when said means are interengaged.

2. In a device of the character described, a stand provided at one side with an upper

angularly extending lip, a board adapted to rest upon said stand, a transverse strap secured to the lower surface of said board and having a downwardly offset portion movable 5 longitudinally into engagement with said lip, and a transverse cleat secured to the lower surface of said board and movable downwardly into engagement with the opposite side of said stand when said strap and 10 lip are interengaged.

3. In a device of the character described, a stand embodying front and rear plates and

a web connecting them, and a board adapted to be carried upon said stand, the front plate and web being adapted to rest on a support, 15 and the rear plate having means engageable under the edge of said support.

In testimony that I claim the foregoing as my own, I have hereto affixed my signature in the presence of two witnesses.

WILLIAM E. SHEPHERD.
